ABSTRACT: A coin-operated lock which comprises a lockbox including a lock bottom and lockbox sidewalls, as well as a lock cover. A cylinder lock is secured to the lock cover including a cylinder core. The latter carries at its end a closing wing including a driver pin. A locking latch has a driver slot and the latter receives the driver pin. A spring-biased locking ratchet is coordinated to the locking latch, and a coin is adapted to be displaced jointly with the locking latch and to lift the locking ratchet with its edge during the advancement. A locking plate is disposed above the locking ratchet sitting rigidly on the locking latch and cooperates in a tumbling-like arrangement with the locking ratchet.

COIN-OPERATED LOCK

The present invention relates to a lock with a locking function to be operable by insertion of a coin.

It is one object of the present invention, to provide a coin-operated lock, which is of simple structure and designed such that a high use safety is present also in view of a nonpermissible locking, and which lock can be equipped with a favorable structure with a device for the return of the coin.

It is another object of the present invention to provide a coin-operated lock, wherein the coin jointly with the latch or the like displaces itself and during its advance lifts with its edge a spring biased locking ratchet coordinated to the latch, whereby a locking plate is provided above the locking ratchet, which locking plate cooperates like a tumbler operation with the locking ratchet sitting securely on the latch.

In accordance with the present invention it is of advantage thereby that the locking plate cooperates with its toothed underside pointing towards the locking ratchet with an angularly shaped end of the locking ratchet.

A favorable structure design is realized, in accordance with the present invention, such, that the locking plate extends parallel above the inner side guide wall of the coin insert slot.

A further advantageous design is obtained, in accordance with the present invention, such, that the pin or the like holding the coin in the coordination to the latch is releasable from its holding position.

In accordance with the present invention it is also of advantage thereby, if the pin or the like sits on a plate displaceable crosswise to the moving direction of the latch, which plate is coupled with an operating key disposed freely to the lock front side against the effect of a spring.

Also an advantageous feature of the present invention resides in the fact, that the operating key is mounted in the latch and runs in a slot guide of the lock housing bottom such that it forms the latch guide.

Also it is of advantage, in accordance with the present invention, that a pressure-button-like operating key runs sunk in the opening of a frame.

Finally, an advantageous solution of the present invention is found in the fact, that the operating key in case of a displaced latch is locked against pushing in, preferably by an arrangement according to which the operating key steps out with its inner end from the opposite position to an escape opening in front of the lock cover.

In view to the particular design a coin-operated lock is created, which is of simple structure with an extremely high security of use. The lock can be framed particularly favorably as a security lock, that means the coin remains after the closing in the lock as security for the key and falls out again when the lock is opened. The lock can, however, be constructed likewise as a collecting lock, that means the coin falls into a closed container. A nondesirable closing of the lock, at which occasion the locking ratchet is brought out of its resting position with the locking latch, by means of a wire inserted through the coin insert slot, is prevented. The locking ratchet enters in case of such sensing advantageously into a locking position with the locking plate rigidly mounted on the locking latch. No coin examiner needs to be present to such coin lock. False coins, which are too small as to their diameter, fall through, while in case of false coins having a too large diameter the locking ratchet is moved by the edge of the coin into a locking position with the locking plate. The locking plate can be provided without any difficulty also still afterwards, for instance, by means of a point welding on the locking latch. The locking plate equipped with a toothed underside is economically manufactured as a stamping part. The angularly shaped end of the locking ratchet is controlled, on the one hand, by the coin from the recess of the locking latch, while, on the other hand, the angularly shaped end assumes in case of a sensing attempt the locking position with the toothed underside of the locking plate. The corresponding locking plate cannot be operated by means of an object inserted into the coin insert slot, as for instance a screwdriver or the like, since it is

disposed above the inner side guide wall of the coin insert slot. The slot can be advantageously equipped without great endeavor with a coin returning device. Erroneously falsely inserted coins or damaged coins can be returned, since a holding

5 pin is releasable from its holding position. This pin is preferably provided on a spring biased plate displaceable substantially crosswise to the moving direction of the latch. The plate carries the operating key, which is freely disposed towards the lock front side. By a slight pressure on the key the pin holding the coin is controlled out of its holding position over the plate. The key mounted in the locking latch serves also for the guide of the locking latch. It runs thereby in a slot guide of the lock-housing bottom. The otherwise necessary latch guide is omitted thereby, so that the coin lock with the coin return device can be produced at a favorable price. The structural arrangement, to provide the pushbuttonlike operating key sunk in the opening of a frame, serves the further increase of the safety of use, since a nonintentional operation of the return device, for instance by cumbersome packages, is to 10 a great extent prevented. The return function is exclusively possible in connection with a completely closed latch, since the operating key enters only in this position in opposite arrangement to the escaping opening of the lock cover arranged 15 in accordance with the present invention. In each other position of the latch the return device is blocked by the lock cover, against which the inner end of the operating key abuts.

With these and other objects in view, which will become apparent in the following detailed description, the present invention, which is shown by example only, will be clearly understood in connection with the accompanying drawings, in which:

FIG. 1 is a back elevation of the coin-operated lock with the locking latch being withdrawn;

FIG. 2 is a front elevation of the coin-operated lock;

FIG. 3 is an elevation similar to that of FIG. 1, however, with the lock cover being removed;

FIG. 4 is a view similar to FIG. 3, however, showing the started closing process;

FIG. 5 is again a front elevation showing the coin-operated lock upon completed closing process in the position in which the key is removable;

FIG. 6 is also an elevation similar to that shown in FIG. 3, wherein the coin-operated lock has a partly withdrawn locking latch and a freed coin;

FIG. 7 is a section along the lines 7—7 of FIG. 3;

FIG. 8 is a section similar to that of FIG. 7, however, with a pushed-in operating key; and

FIGS. 9—11 are fragmentary elevations in an enlarged and simplified showing of the locking plate in different positions of the locking latch.

Referring now to the drawings, the coin-operated lock comprises a lockbox 1.

The lockbox 1 has sidewalls 3, 4, 5 and 6, which extend at 55 an angle from the lock bottom 2. The lock guard is covered up by the lock cover 7, which is secured by means of securing screws 8. The latter enter in distancing bushings 9 and 9', respectively.

A cylinder lock 10 is secured to the cover 7. Its cylinder core 12, operable by means of a key 11 extends into the inside of the lock. It carries at its end a closing wing 13, the driver pin 14 of which extends into a driver slot 15 or the closing latch 16.

65 A locking ratchet 17 is swingably mounted above the locking latch 16 about the distancing bushing 9'. A holding spring 18 bent like a hairpin and disposed about the distancing bushing 9' engages the locking ratchet 17 in the direction of the corresponding narrow longitudinal side 19 of the locking latch 16. The narrow longitudinal side 19 is there equipped with a recess 20 into which the angularly bent end 17' of the locking ratchet 17 enters.

70 The locking ratchet 17 is coordinated above the latter to a locking plate 21 sitting rigidly on the locking latch 16. The latter has a toothed bottom side including the recesses 22, 23 and 24.

The locking plate 21 is disposed in the lockbox 1 on the locking latch 16 such, that it extends parallel above the inside guide wall 25 of the coin insert slot 26. The coin insert slot 26 started in the lockbox wall 3.

In accordance with FIGS. 1 to 3, the lock is disposed in open position. The key 11 is not removable in this position. The angularly bent end 17' of the locking ratchet 17 disposed in the recess 20 prevents a closing of the locking latch 16. By a coin insert, and starting closing of the lock 16, the locking ratchet 17 is brought out of engagement with the recess 20 over the coin edge (see FIG. 4). The coin 28 is now advanced by the pin 29 over the supporting shoulder 27, until it slides away from the supporting shoulder 27, whereby the resilient locking ratchet 17 accelerates shocklike the coin fall. Thereafter the position shown in FIG. 5 is obtained, in which position the coin 28 is disposed in the mentioned coin-storing chamber. Exclusively in this position can the key 11 be removed by the user. The coin remains as a deposit, until the user opens again the lock, whereby the coin-storing chamber is located above the coin outlet slot 37 and the coin falls out (see FIG. 6).

If the same above-described lock is to be used as a collecting lock, it is necessary to coordinate a cassette to the coin outlet slot 37.

If due to damaged or erroneously falsely inserted coins a return of the latter should take place, the operating key 31 is pushed whereby the pin 29 is moved over the plate 30 from its position holding the coin 28, so that the coin passes through and emerges from the slot 38 (see FIG. 8). In case of the latch 16 being advanced, the operating key 31 is locked against the lock cover 7. In the basic position of the lock, the coin return device can be successfully operated at any time. In this position the operating key 31 is disposed within the range of an escape opening 41 of the lock cover 7 (see FIG. 1), so that the plate 30 can be displaced a further required length causing the freeing of the coin. Below the insert slot is provided a supporting shoulder 27 on the lock bottom 2, which supporting shoulder limits jointly with a pin 29 the insert movement of the coin 28. The pin 29 sits on a plate 30 displaceable crosswise to the direction of movement of the locking latch 16 and passes through an opening 16' of the locking latch 16. The corresponding plate 30 is abutted by the blade spring 13 in the direction towards the wide side of the locking latch 16.

The pushbuttonlike operating key 31 is secured to the plate 30, which operating key 31 is mounted in a bushing 32 of the locking latch 16. The bushing 32 runs in a guide slot 33 of the lock bottom 2, whereby the locking latch guide is formed. The guide slot 33 is framed in accordance with the slot contour. The corresponding frame 39 has such thickness, that the head 31' of the operating key 31 is sunk in and is thereby disposed protected in the frame opening 40.

The locking latch 16 stands under the effect of a latch spring 34 disposed on the bushing 9', which latch spring 34 retains the locking latch 16 in its prevailing abutment position.

At the front side of the locking latch 16 is provided a bent-over stay 35 which guides the coin 28 by means of a plate 36 sitting on the locking latch 16. The coin-storing chamber formed by the stay 35 and the plate 36 can be brought into a flush position with a coin outlet slot 37 of the lockbox wall 4 depending upon the position of the locking latch 16.

Coins which are too small, the diameter of which is smaller than the distance between the supporting shoulder 27 and the pin 29, fall through and fall out of the slot 38.

The operation of the keylock is as follows:

The locking plate 21 equipped at its underside with toothed recesses 22, 23 and 24 does not disturb the closing function of the lock in case of a correctly inserted coin. A false coin and a coin having a larger diameter would move during the closing process the locking ratchet 17 into the position indicated in point-dotted lines in FIG. 9. The angularly shaped end 17' enters into the toothed recess 22 of the locking plate 21. The closing movement is not performable, due to this locking. Likewise, these toothed recesses prevent a closing of the locking latch 16 if in a nonpermissible manner the locking

5 ratchet 17 is brought from the engaging effect with the opening 20 of the locking latch 16 by means of a wire put through the coin insert slot 26 and if the angular end 17' enters the toothed opening 22, 23 or 24 (see FIGS. 9 to 11).

While I have disclosed one embodiment of the present invention, it is to be understood that this embodiment is given by example only and not in a limiting sense.

I claim:

1. A coin-operated lock, comprising a lockbox including a lock bottom and lockbox sidewalls, as well as a lock cover, a cylinder lock secured to said lock cover including a cylinder core, the latter carrying at its end a closing wing including a driver pin, a locking latch having a driver slot and the latter receiving said driver pin, a spring-biased locking ratchet being coordinated to said locking latch, and a coin being adapted to be displaced jointly with said locking latch and to lift said locking ratchet with its edge during the advancement, a locking plate disposed above said locking ratchet sitting rigidly on said locking latch and cooperating in a tumbler-like arrangement with said locking ratchet, pin means adapted to hold said coin in relation to said locking latch, means for releasing said pin means from said holding position, a plate mountable transverse to the direction of movement of said locking latch, a spring-biased operating key disposed accessible from the front side of said lock and coupled with said plate, and said pin means sitting on said plate.
2. The coin-operated lock, as set forth in claim 1, wherein said operating key is mounted in said locking latch and runs in a slot guide of said lock bottom, to form a guide for said locking latch.
3. The coin-operated lock, as set forth in claim 1, which includes a frame secured to the bottom of said lockbox, and said operating key is sunk in an opening of said frame. The coin-operated lock, as set forth in claim 1, wherein said operating key moves with its inner end to an escape opening in said lock cover, in order to lock said operating key against being pushed in in case of a displacement of said locking latch.
- 50 5. A coin-operated lock operable by a key upon inserting a coin, comprising a displaceable locking latch having a recess, a spring-biased locking ratchet having an angular bent end and releasably engaging in said recess of said latch, a locking plate disposed tumblerlike over said locking ratchet, said locking plate having projections pointing toward said locking ratchet, being successively toothlike, and being rigidly connected with said latch, an immovable supporting shoulder, a pin operatively connected to said latch, said pin and said shoulder arranged to hold a coin and upon start of movement of said latch to move said coin so as to raise said locking ratchet, said pin, supporting shoulder, locking ratchet and locking plate arranged such that at a start of advance of said latch, a properly sized coin inserted in said coin operated lock lifts said ratchet with its edge out of said recess nonengaging with said projections of said locking plate, as well as such that an undersized coin does not raise said ratchet out of said recess, thereby preventing movement of said locking latch, and such that an oversized coin raises said locking ratchet out of said recess into engagement with one of said projections of said locking plate, thereby preventing movement of said latch, and

a pressing key operatively connected to said pin and releasable from the outside for moving said pin out of holding cooperation with said coin, thereby causing said coin to be returned away from its held position by said shoulder and pin.

6. The lock, as set forth in claim 5, wherein
said pin is operatively held on said locking latch,
said pin in a basic position of said locking latch is sup-
ported on said immovable supporting shoulder,
a coin-storing chamber disposed beneath said supporting
shoulder and operatively connected to said locking latch,
said pin moving said coin in a preliminary closing position of
said latch over said supporting shoulder away from said
holding of said coin into a lower holding position in said
coin-storing chamber,
a coin outlet slot in said coin-operated lock,
said coin-storing chamber reaches an aligned position com-

municating with said coin outlet slot in a returned position of said locking latch, whereby said coin is returned.

7. The lock, as set forth in claim 5, wherein
said projections on said locking plate defining a plurality of
stepped-up recesses in its on its bottom side pointing
towards said locking ratchet, and
said angular bent end constituting a toothed projection of
said locking ratchet extending between two of said
stepped-up recesses is disposed above said supporting
shoulder.

8. The lock as set forth in claim 5, further comprising
a coin insert slot means,
an inside guide wall of said coin insert slot,
said locking plate extends parallel to and above said inside
guide wall.
